UNITED STATES PATENT OFFICE.

ALFRED L. BERNARDIN, OF EVANSVILLE, INDIANA.

BOTTLE-CAP.

1,355,446.

Specification of Letters Patent. Patented Oct. 12, 1920.

Application filed November 17, 1917. Serial No. 202,558.

To all whom it may concern:

Be it known that I, ALFRED L. BERNARDIN, a citizen of the United States, and a resident of Evansville, in the county of Vanderberg and State of Indiana, have invented 5 a new and useful Improvement in Bottle-Caps, of which the following is a specification.

My present invention relates generally to 10 bottle caps and more particularly to bottle caps of that type applicable to catsup bottles and the like and whose purpose is to enable the user to readily associate the same with and disassociate the same from a bottle 15 in use during the ordinary consumption of the contents thereof.

To this end my present invention proposes the utilization of a cap the construction of which obviates use of the usual 20 threads on the bottle and the cap and consequent turning movement of the cap in applying and removing the same and which for this purpose has means engageable with 25 coöperating means formed upon the bottle neck whereby the cap may be connected with and disconnected from the bottle by wholly rectilinear movements thereof.

More especially my invention proposes a 30 cap having indentations for engagement with a bottle neck rib and of such character as to not only hold the cap normally upon the bottle but to provide for its placement and removal for substantially an indefinite number of times and with maximum effectiveness throughout its use.

My invention resides in a cap having one or more indentations whose transverse axis or axis of shortest length is parallel to the longitudinal axis of the cap and is of such 40 length that the base of the indentation is flat for an appreciable distance so as to lend greater strength without impairing resiliency and in this way enable the cap to be placed upon and removed from a bottle neck for an indefinite number of times without diminishing its effectiveness.

In the accompanying drawing illustrating my invention—

Figure 1 is a vertical section through a 50 cap embodying my present improvement illustrating the same as in use upon a bottle neck,

Fig. 2 is an elevation of the same,

Fig. 3 is a partial vertical section illustrating the cap partly associated with the 55 bottle,

Fig. 4 is a similar view illustrating the cap fully engaged,

Fig. 5 is a horizontal section taken substantially on the line 5—5 of Fig. 1, 60

Fig. 6 is an elevation illustrating the invention as applied to a cap of slightly different construction from that shown in Fig. 5.

Referring now to Figs. 1 to 5 in particular my invention proposes the utilization of indentations 10 in the skirt portion 11 of a bottle cap 12, the latter of which may be of various constructions as to its particular make-up, for instance what is 70 known as a pieced construction as seen particularly in Figs. 1 and 2, or a seamless drawn construction 13 as seen in Fig. 6, wherein the indentations are shown at 14.

The cap in connection with which the invention is utilized may have a reinforcing bead 15 around its open end or may terminate in a raw edge as seen at 16 in Fig. 6.

Irrespective of the construction of the cap other than the indentations 10, it is proposed to utilize the same in connection with a bottle whose neck 17 is provided with a rib 18 adjacent its mouth, the rib extending entirely around the bottle neck in an unbroken manner and being preferably 85 rounded as shown in order to provide for more ready connection and disconnection of the cap.

The cap is also preferably used in connection with a bottle neck having the usual 90 lip around its mouth for the reception of a suitable seal as for instance the well-known "crown" seal 19 as illustrated in Fig. 1 which is associated with the bottle to seal the same when the latter receives its contents and is filled in the first instance, the cap 12 being placed over the crown seal so that upon removal of the latter by the consumer the cap 12 may be utilized during normal consumption of the contents of the 100 bottle to prevent oxidation of the contents thereof.

As illustrated an annular series of indentations 10 appear, it being obvious from an inspection of the several figures that irrespective of their number, each of the indentations has its transverse axis which is parallel to the longitudinal axis of the cap, of such length as to produce a flattened base 20 in each indentation, or in other 110 words a base which for some distance is parallel to the plane of the wall of the cap.

This structure is such that maximum elasticity is brought about and the cap may be placed upon and removed from the bottle an indefinite number of times without diminishing its effectiveness and being possessed of considerably greater strength than it would otherwise have, the clasp of the cap in connection with the bottle in operative position is such as to obviate its accidental displacement and at the same time permit of its removal by a quick jerk.

The indented form of cap as proposed in this application and as distinguished from a cap and bottle having interacting threads, obviously embodies considerable advantage by virtue of the speed and ease with which the cap may be removed and replaced and is further of great advantage by virtue of its adaptability to various types of caps in respect to their particular formation or make-up irrespective of the indentations and to which threads are either inadaptable or difficult of adaptation.

I claim:—

1. A bottle cap of the type described having an indented portion at its open end, the transverse axis of which is parallel to the longitudinal axis of the cap and the

base of which is flattened over a considerable area and is adapted to tangentially engage the neck of a bottle in a plane substantially parallel to its axis whereby frictional engagement is secured without material distortion of the cap flange when the cap is removed.

35

2. A bottle cap of the type described having an indented portion adjacent its free edge for engagement with a bottle neck rib, said indented portion having a base of substantial area approximately parallel to the plane of the wall of said cap, that is adapted to tangentially engage the neck of a bottle in a plane substantially parallel to its axis whereby frictional engagement is secured without material distortion of the cap 45 flange when the cap is removed.

3. A bottle cap of the type described having an annular series of indentations adjacent its open end, each of which indentations is provided with a flattened base that is adapted to tangentially engage the neck of a bottle in a plane substantially parallel to its axis whereby frictional engagement is secured without material distortion of the cap flange when the cap is removed.

50 ALFRED L. BERNARDIN.
